UNITED STATES PATENT OFFICE.

THOMAS E. ALLEN, OF ANDOVER, MASSACHUSETTS.

METHOD AND MEANS FOR LUBRICATING BEARINGS.

1,170,213.

Specification of Letters Patent.

Patented Feb. 1, 1916.

Application filed October 16, 1915. Serial No. 56,320.

To all whom it may concern:

Be it known that I, THOMAS E. ALLEN, a citizen of the United States, residing at Andover, in the county of Essex and State 5 of Massachusetts, have invented an Improvement in Methods and Means for Lubricating Bearings, of which the following is a specification.

This invention relates to certain improvements in methods and means for lubricating bearings, and more particularly to that class 10 of bearings which are self-lubricating.

Prior to my invention it has been customary to pack the upper portion of a journal box with a fibrous material saturated with hard grease, "yarn grease" being a well-known form of such material. When this is employed, it is found that, after a time, the portion of the lubricating material, 15 which rests directly against the shaft, becomes caked with a hard, impervious substance which prevents effective lubrication of the bearing. Lubricating oil, when supplied by various well-known means, requires 20 more or less constant attention, and is a more expensive method of lubrication than that above referred to.

The object of my invention is to provide a method and means of lubrication, whereby 25 the grease-saturated material may be effectively employed and the formation of an impervious coating thereon may be prevented, so that a bearing may be sufficiently lubricated for long periods, without attention, and at small expense. I accomplish 30 these objects by providing a mass of grease-saturated material in one side of a bearing box casing and supplying a relatively small quantity of lubricating oil to the shaft at 35 such a point that the oil is carried directly beneath the material before it is carried to the bearing.

An embodiment of means whereby the method above referred to, and hereinafter 40 described, may be successfully performed, is illustrated in the accompanying drawing, in which;—

Figure 1 is a cross-sectional view, taken at the line 1—1 of Fig. 2, of a bearing embodying my invention. Fig. 2 is a plan view of the bearing.

The journal-box *a* is of well-known construction, and adapted to receive the lower half of a shaft *b*, which rests therein. A 45 box or casing *c* is mounted on the upper side of the journal box, and incloses the upper

half of the shaft, or portion above the level of its axis, in a well-known manner, said casing being provided with a cover *d*.

According to my invention, an oil reservoir *e* is supported in one side of the casing *c*, above the shaft *b*, and at the side thereof from which the portion of the shaft, above the level of its axis, moves. A piece of wicking *f*, which is approximately as wide 60 as the length of the bearing, is connected to the upper edge of the reservoir *e*, and depends from over its side, so that its end-portion *f'* lies on the uppermost portion of the shaft, and extends in the direction in 65 which the shaft rotates, as indicated by the arrow in Fig. 1. A series of feeding strings *g* are connected to the opposite end of the wick, and extend down into the lubricating oil *h*, with which the reservoir *e* is partly 70 filled. The space in the opposite half of the casing *c*, beyond the end *f'* of the wicking, or between the shaft and the opposite side of the casing *c* from that in which the reservoir *e* is located, is partly filled with yarn- 75 grease *i*, or other suitable fibrous material, saturated with a hard grease, so that it rests directly on the shaft and is held in place 80 thereon by the side of the casing *c*, against which the shaft tends to carry it.

In operation, the oil will be fed by the strings *g* to the wick *f*, and by the wick to the shaft, by capillary attraction, so that, as the shaft revolves, a very thin film of oil will be applied thereto, this method of lubrication, *per se*, being well known. The oil thus applied to the shaft is immediately carried by the shaft into contact with the grease-saturated material *i*. I have ascertained that, by thus furnishing a lubricating 95 oil directly to the shaft-engaging surface of the grease-saturated material, before it passes into the bearing box, the oil acts to soften the grease at said surface, and to prevent the caking or the formation of an 100 impervious surface on said material, so that the latter is constantly maintained in its original condition. As a result, the shaft will be effectively lubricated for long periods without attention, the amount of oil 105 which is supplied being much less than if it were employed alone, so that the above-described method of lubrication is inexpensive, as well as effective; the effectiveness of oil-lubrication and the economy of 110 the grease-saturated fiber lubrication being practically secured.

The above-described arrangement may be readily applied to any journal box of the type illustrated.

I claim:—

- 5 1. The method of lubricating shafts which consists in supporting a mass of fibrous material, saturated with hard-grease, on a portion of the surface of the shaft, to be lubricated, above the level of its axis, 10 and providing a constant supply of lubricating oil to an adjacent portion of said surface above said level, so that the oil is carried directly beneath said material, by the shaft, as it rotates.
- 15 2. A self-lubricating bearing comprising a journal box having a shaft resting therein, a casing inclosing the portion of the shaft above the bearing, a fibrous, grease-saturated material, resting on the shaft, between the shaft and the side of the casing toward which the shaft turns, and means in the opposite side of the casing to supply lubri-

cating oil to the surface of the shaft, above its axis, as it moves toward the packing.

3. A self-lubricating bearing comprising 25 a journal box having a shaft resting therein, a casing inclosing the portion of the shaft above the bearing, a fibrous, grease-saturated material resting on the shaft, between the shaft and the side of the casing toward 30 which the shaft turns, an oil reservoir located in the opposite side of the casing from said material, and a wick leading from said reservoir and resting on the shaft in proximity to said material in such a position, 35 with relation to the direction of rotation of the shaft, that the oil will be carried beneath said material before passing to the journal box.

In testimony whereof, I have signed my 40 name to this specification.

THOMAS E. ALLEN.
